(57) **CLAIM**

An ornamental design for a two shell and slide cigarette packs joined side-to-side with outerwrap, as shown and described.

DESCRIPTION

FIG. 1 is a perspective view of two shell and slide cigarette packs joined side-to-side with outerwrap, showing our new design;

FIG. 2 is a left side elevational view thereof without outerwrap, the right side elevational view being identical; FIG. 3 is a rear elevational view thereof without outerwrap; FIG. 4 is a front elevational view thereof without outerwrap; FIG. 5 is a top plan view thereof without outerwrap, the bottom plan view being identical; and,

FIG. 6 is a perspective view of two shell and slide cigarette packs joined side-to-side with outerwrap with the slide of each pack outwardly of the shell, showing our new design. The outerwrap has been removed from the disclosures of FIGS. 2-6 for convenience of illustration.
